UNITED STATES PATENT OFFICE.

WILLIAM R. ALLEN, OF CLEVELAND, OHIO, ASSIGNOR TO THE AMERICAN MULTIGRAPH COMPANY, OF CLEVELAND, OHIO, A CORPORATION OF OHIO.

TYPE.

1,078,400.

Specification of Letters Patent.

Patented Nov. 11, 1913.

Application filed November 6, 1912. Serial No. 729,742.

To all whom it may concern:

Be it known that I, WILLIAM R. ALLEN, a citizen of the United States, residing at Cleveland, in the county of Cuyahoga and

5 State of Ohio, have invented a certain new and useful Improvement in Type, of which the following is a full, clear, and exact description, reference being had to the accompanying drawings.

10 One of the objects of this invention is to provide type (including individual type, logotypes and line slugs) in a form which may be conveniently and effectually mounted on the periphery of a drum and will interlock with each other and thus not work out of place.

Another object is to do away with the necessity of end clamps for the lines, as the interlocking sides will hold type in place.

20 Another object is to make the type in such form that it may be used interchangeably about the periphery of the drum or on a flat bed.

Another object is to provide the interlocking projections in such form that they may be conveniently cast or milled from standard type.

To accomplish the desired objects I form my type sides with oppositely positioned

30 ribs and recesses, which may be grooves or rabbets, and extend lengthwise of the line. The ribs which may be part of the original body of standard type, have their sides parallel with the central plane of the type; the

35 grooves or rabbets, however, have their bottoms in planes which are parallel to the central planes of contiguous similarly formed type standing radially about the drum. Accordingly it results that when the type are

40 set up with the ribs of one type occupying the grooves or rabbets of adjacent type, both type being radially placed about the drum, the type stand on the drum as if they were wedge shaped or their opposite sides radial.

45 Wedge shaped type, however, have a tendency to work off their feet and when they do so work the form is thereby loosened. The interlocking action of my type prevent them from working off their feet and main-

50 tain the form in proper position for printing.

Another application filed by me concurrently herewith and numbered Serial No. 729,743, shows and claims broadly the feature of type having its sides constructed in

two planes, one of which is parallel with the central plane of the type itself and the other of which is parallel with the central plane of a contiguous similarly formed type. In the embodiment shown in that application, however, the ribs and grooves extend in an up and down direction from the base of the type to the face. In the present invention I make the ribs and recesses so that in the line of type or on a slug they extend lengthwise of the line or parallel with the face of the type. One of the advantages of the present system of interlocked type is that it readily adapts itself for locking up individual type in the same line with linotypes.

The type of this application, as well as that shown in my other application referred to, may be locked up on a flat bed as well as mounted radially about a drum, it being only necessary when mounting it on a flat bed to put leads between successive type lines to prevent the ribs on one type entering the grooves of another.

My invention is hereafter more fully described and its essential characteristics set out in the claims.

In the drawings Figure 1 is a perspective view of a line of type made in accordance with this invention; Fig. 2 is a perspective view looking at the opposite side of a line composed partly of individual type and partly by a line slug; Fig. 3 is an edge view of several of the type mounted about the periphery of a drum, this view being on an enlarged scale; Fig. 4 is a plan of several lines of the type mounted on a flat bed or galley; Fig. 5 is an edge view of the type so mounted.

As shown in the drawings 1 represents the type which may have characters 2 on its face. 95 On one side of the type, as shown herein, are two flat faces or ribs 3 and 4 between which is a groove 5; in the other side of the type is a central or intermediate flat face or rib 6, and cut away portions or rabbets 7 and 8 100 are formed below and above the ribs 6. The surfaces 3, 4 and 6 are parallel with each other and parallel with the central plane of the type and may be part of the original surface of standard type; the surface 5 is parallel with the central plane of a similar type 1 nesting with the type under discussion on its right hand side; the surfaces 7 and 8 are

parallel with the central plane of a similar type nesting against the left hand side of the type under discussion.

The depth of the inclined cuts 5, 7 and 8

5 depends upon the dimensions of the type and the diameter of the drum about which they are to stand. When the type are mounted about the proper drum the central plane of each type is a radial plane of the drum, and 10 as stated, the side surfaces of the type are parallel with some radial plane passing through the center of the type line, either the center of the line itself or one of the contiguous lines. As the types are adapted to 15 stand snugly on the periphery of the drum, it follows that the plane through the face of the grooves goes as much to one side of the center of the drum as the plane through the face of the ribs passes to the other side, 20 and accordingly, that a radial plane through the abutting outer corners of the type pass midway between the rib plane and the groove plane. Therefore, the faces of the grooves at any point stand back from the 25 rib plane twice the distance which the radial plane through the outer corner of the type stands back from such rib plane. This characteristic is explained more fully in connection with geometrical and algebraic proof 30 and formulae in my application No. 729,743 above referred to.

Lines of type, of the form described, may be mounted about the periphery of a drum as accurately as if they were all wedge shaped, but by reason of each type having on opposite sides some surfaces which are parallel with the central plane of the type it is possible also to lock the type up on a flat bed by simply placing leads between the lines. 40 This is clearly illustrated in Figs. 4 and 5 where the leads are shown at 10, the individual type at 1, and one of the linotypes at 9.

Another feature of my interlocking type is that as each type locks to the next one it is only necessary to secure the endmost lines of type to lock the whole form on the drum. This is illustrated in Fig. 3 where the end line of type is shown as resting against a block 12 locked to the drum 13 by a set screw 14. The block has a groove 15 in which the ribs 6 of the endmost line seat, and this line holds the next line, and it holds the next one, and so on; so that it is only necessary to hold 55 the form at the opposite end, which may be done by a block similar to the block 12, but having a rib to enter the groove 5. It is not necessary to lock the type from the ends. Any suitable closure may be used to prevent 60 their undue spreading within the line, and additional type may be put in the line or type removed endwise, as desired.

A further advantage of my interlocking type over the standard form, and over wedge shaped type, is that each type only nests

with the next line when all the type in that line stand with their characters facing in the same direction, so that there is no danger of printing any character upside down.

Having thus described my invention, what 70 I claim is:

1. A type adapted to seat on a drum and interlock with type in a contiguous line, such type having its opposite sides formed in two planes, one of which is parallel with 75 the central plane of the type itself and the other of which is parallel with the central plane of the type in such contiguous line, the side surfaces being located one above another measuring from the foot of the type 80 to its face.

2. A type of the character described adapted to be mounted on a drum and having its side surfaces formed of ribs and recesses alternately one above another, the 85 ribs being parallel with the central plane of the type, and the recesses being parallel with the central plane of a similar type mounted in a contiguous line on the same drum.

3. A type having a character on one end 90 and having its opposite sides formed of sections one above the other, some of said sections being parallel with the central plane of the type and others of said sections parallel with the central plane of a similarly 95 formed adjacent type standing at an angle to the type first mentioned.

4. A type having a character on its edge and having its side formed of alternate ribs and recesses located one above the other, the 100 ribs having their surfaces parallel with the central plane of the type and the recesses being inclined with reference to such plane.

5. A type of the character described, wherein the sides are broken up into ribs and recesses one above the other, the ribs having 105 their surfaces parallel with the central plane of the type, and the recesses being formed by surfaces which incline from the planes of the ribs toward the central plane of the type.

6. A type having its sides formed of alternate ribs and recesses one above the other, the ribs having their outer faces composed of flat surfaces lying in the original side planes of the type, and the recesses being 115 within the original side planes of the type, and having their faces at an acute angle to the central plane of the type.

7. A type having its side surfaces broken up by alternate ribs and recesses located one 120 above the other, the ribs on one side of the type standing opposite the recesses on the other side and vice versa, the ribs having their surfaces parallel with the central plane of the type, and the recesses being located 125 within the planes bounding the ribs.

8. As a new article of manufacture, an interlocking type adapted for mounting on the periphery of a drum or on a flat bed, said type having its sides broken up into a 130

plurality of steps one above the other, some of which are parallel with the central plane of the type and others of which are parallel with the central planes of similarly formed 5 contiguous type standing radially on the same drum.

9. A type having its sides formed of alternate ribs and recesses, the ribs being parallel with the central plane of the type and the 10 recesses being inclined to such plane and located between the planes bounding the sides of the type, the ribs on one side of the type coming opposite the recesses on the other.

15 10. As a new article, a type, the edge of which has a character and the sides of which have alternate ribs and recesses located one above the other, the ribs having their outer 20 faces plane surfaces which are parallel with the central plane of the type, and the recesses on opposite sides having their faces oppositely inclined with reference to such plane.

11. A type having on its sides ribs and 25 recesses one above the other, the ribs having their outer faces plane surfaces which are parallel with the central plane of the type and the recesses having their faces inclined at an acute angle to said central plane.

12. A type having on its sides ribs and 30 recesses one above the other, the ribs having their outer faces plane surfaces which are parallel with the central plane of the type and the recesses having their faces inclined at an acute angle to said central plane, the 35 ribs on one side of the type being directly opposite the recesses on the other side.

13. A type having on its sides ribs and recesses one above the other, the ribs having 40 their outer faces plane surfaces which are parallel with the central plane of the type and the recesses having their faces inclined at an acute angle to said central plane, the ribs on one side of the type being directly opposite the recesses on the other side.

45 and the recesses having their faces inclined at an acute angle to said central plane, the ribs on one side of the type being directly opposite the recesses on the other side, and each rib having substantially the same up-and-down dimension as the directly opposite recess on the other side, whereby when contiguous lines are mounted on a drum they 50 may interlock.

14. As a new article of manufacture, a 55 type having on its sides alternate ribs and recesses located one above the other, the ribs having their faces parallel with the central plane of the type and the recesses inclining from that plane at an angle thereto which is twice the angle which is made with that plane by a radial plane from the center of the drum on which the type are adapted to seat through the outer corner of the type.

15. The combination of type formed to 60 seat compactly on the periphery of a drum and interlock with each other and also to stand compactly on a planular surface, each type having the characteristic that its sides are composed of alternate ribs and recesses, 65 one above the other, the face of the ribs being parallel with the central plane of the type and the face of the recesses being at an angle with the ribbed plane equal to twice the angle which the radial plane of the 70 drum through the outer corner of the type thereon makes with the rib plane.

In testimony whereof, I hereunto affix my signature in the presence of two witnesses:

WILLIAM R. ALLEN.
